WRENCH

Oscar D. Legg, Athens, Ala.

Application September 23, 1936, Serial No. 102,207

2 Claims. (Cl. 81—91)

The invention relates to a wrench and more especially to a pipe wrench.

The primary object of the invention is the provision of a wrench wherein through the use of a runner upon the shank, the inner jaw can be set with respect to the outer jaw so that work can be firmly and securely gripped for the turning thereof.

Another object of the invention is the provision of a wrench wherein the inner jaw is susceptible of rocking adjustment with respect to the outer jaw thereby adapting the wrench to different sizes of work and particularly pipes of varying cross sectional diameters.

15 A further object of the invention is the provision of a wrench wherein the construction thereof is novel in form, particularly with respect to the mounting of the inner jaw and its adjustment with respect to the outer jaw.

20 A still further object of the invention is the provision of a wrench which is extremely simple in its construction, thoroughly reliable and efficient in operation, readily and easily adjusted, possessing maximum strength and durability, 25 and inexpensive to manufacture.

With these and other objects in view, the invention consists in the features of construction, combination and arrangement of parts as will be hereinafter more fully described, illustrated in 30 the accompanying drawing, which discloses the preferred embodiment of the invention and pointed out in the claims hereunto appended.

In the accompanying drawing:

Figure 1 is a side elevation of a wrench constructed in accordance with the invention.

Figure 2 is a view similar to Figure 1 showing an adjustment of the wrench.

Figure 3 is an enlarged fragmentary sectional view taken on the line 3—3 of Figure 1 looking 40 in the direction of the arrows.

Similar reference characters indicate corresponding parts throughout the several views in the drawing.

Referring to the drawing in detail, the wrench 45 constituting the present invention comprises a shank 10 having flattened opposite faces 11 and opposed threaded surfaces 12, respectively, these being coextensive for a major portion of the length of said shank. At the outer end of the 50 shank 10 is a pivot ear 13 carrying a pivot 14 of swingingly connecting the straight stem 15 of an outer jaw 16 with the shank, said jaw having the serrated curved work engaging face 17 relatively wide to assure the gripping of a piece of 55 work firmly.

Rotatable on the shank 10 is an internally threaded feed sleeve 18, the internal threads 19 being engaged with the threads 12 on the said shank. This sleeve constitutes a runner and is formed with a reduced end portion 20 loosely 5 embraced by a collar 21 having the pivot ear 22 carrying a pivot 23 which swingingly mounts a link 24. The link is outwardly curved and this link at its ear 25 carries the pivot 26 which connects the link with a movable inner jaw 27 having the serrated work engaging face 28. The movable jaw 27 is adjustably and swingingly connected by a pivot pin 29 with the stem 15, the latter having the holes 30 spaced apart therein for selectively accommodating said pin. In this 10 manner the jaw 27 can be moved relative to the jaw 16 according to the size of work to be gripped by these jaws.

The collar 21 is loosely held on the reduced end 20 of the sleeve 18 by a retaining nut 31 20 and thus the sleeve can be freely rotated on the shank 10. This sleeve 18 is formed with flattened outer faces 32 to enable the grasping thereof by the hand so that said sleeve can be turned or rotated upon the shank to effect the rocking adjustment of the jaw 27 relative to the jaw 16 of 25 the wrench.

The collar 21 at diametrically opposite sides has formed therewith frictional guide fingers 33 which engage with the flattened opposite faces 11 of 30 the shank 10 to avoid the turning of the collar when the sleeve 18 is rotated to swingably adjust the jaw 27, these fingers being in sliding contact with the said flat faces 11 of the shank throughout the travel of the sleeve. Furthermore, the fingers 33 will brace the collar 21 35 against any canting action exerted by the link 24 tending to cause the collar to bind on the sleeve 18 so that the sleeve may always turn freely.

The shank has fitted thereto a suitable handle 40 or grip 34.

The wrench at the working faces 17 and 28 of the jaws 16 and 27 is relatively wide to assure a broad gripping action upon the work such as a pipe or other article to be turned. The serrated 45 faces 17 and 28 will assure biting action of the jaws on the work to avoid any possibility of the slipping of the jaws thereon.

What is claimed is:

1. A wrench of the character described comprising a shank, a sleeve threaded on said shank, a collar encircling said sleeve, a jaw having a stem pivoted to said shank, a second jaw pivoted to the stem and adjustable thereon, a link pivoted to the collar and to said last-mentioned jaw, and 50 55

fingers on the collar and frictionally engaging opposite faces of the shank for preventing turning of the collar on the turning of the sleeve.

2. A wrench of the character described comprising a shank, a sleeve threaded on said shank, a collar coupled with said sleeve, a jaw having a stem pivoted to said shank, a second jaw pivoted to the stem and adjustable thereon, a link pivoted

to the collar and to said last-mentioned jaw, and fingers on the collar and frictionally engaging opposite faces of the shank for preventing turning of the collar on the turning of the sleeve, the said stem having a plurality of openings and a separable pivot for the last-mentioned jaw and selectively engageable in said openings. 5
